Dec. 14 68

Charles A. Shaw, of Biddeford, Maine.
Whole No. 1468. Letters Patent No. 103, dated Aug. 13, 1861.

The schedule referred to in these Letters Patent and making part of the same.

To all to whom these presents shall come, greeting:

Be it known, that I, Chas. A. Shaw, of Biddeford, in the County of York and State of Maine, have invented or produced a new and original design for a work holder, and I hereby declare that the following is a full, and exact description of the same, reference being made to the accompanying drawings.

The nature of my invention or production will be seen by the drawings and the following description, and consists in placing upon the wire framework of the work holder a a metallic top piece struck up by a die in the form of a honey bee, so arranged upon the holder as to make the bee appear to be holding the wires or hooks of the work holder by means of its forward legs. The form and appearance of the honey bee is so familiar that a more elaborate description is deemed unnecessary.

What I claim as my invention and desire to have secured to me by Letters Patent is, the design for a work holder as above described and illustrated in the accompanying drawings.

Witnesses,

Edwin Fuller.
Geo. H. Adams.

Charles A. Shaw.

Geo. H. Adams.
